United States Patent Office

Des. 214,313
Patented June 3, 1969

214,313

MOTORIZED GOLF CART

Norman S. Gardner, 64 Trenor Drive,
New Rochelle, N.Y. 10804

Filed Aug. 26, 1968, Ser. No. 13,259

Term of patent 14 years

Int. Cl. D12—13

U.S. Cl. D14—3

FIG. 1

FIG. 2

FIG. 3

FIG. 4

FIG. 5

FIG. 6

FIG. 1 is a top plan view of a motorized golf cart showing my new design;

FIG. 2 is a left side elevational view;

FIG. 3 is a front view;

FIG. 4 is a rear view;

FIG. 5 is a bottom plan view; and

FIG. 6 is a right side view showing the rack in a different position of adjustment.

The golf bag and clubs, shown in broken lines in FIGURE 6, are included for illustrative purposes only.

I claim:

The ornamental design for a motorized golf cart, substantially as shown and described.
